UNITED STATES PATENT OFFICE.

EBERHARD L. PUPKE, OF NEW YORK, N. Y.

LOCK FOR FIRE-ARMS.

SPECIFICATION forming part of Letters Patent No. 409,704, dated August 27, 1889.

Application filed December 19, 1888. Serial No. 294,093. (No model.)

To all whom it may concern:

Be it known that I, EBERHARD L. PUPKE, a citizen of the United States, residing at New York, in the county of New York and State 5 of New York, have invented certain new and useful Improvements in Fire-Arms; and I do hereby declare the following to be a full, clear, and exact description of the invention, such as will enable others skilled in the art to 10 which it appertains to make and use the same.

My invention relates to certain new and useful improvements in trigger mechanisms for double-barreled fire-arms, and has for its 15 object to provide a simple and effective device whereby the hammers of a double-barreled gun may be sprung alternately by the manipulation of a single trigger.

With these ends in view my invention consists in the details of construction and combination of elements, such as will be herein-after fully set forth, and then specifically designated by the claims.

In the accompanying drawings, Figure 1 is 25 a sectional elevation of a gun-breech, showing the relative position of my improved trigger mechanism to the sears; Fig. 2, a section at the line $x-x$ of Fig. 1, and Fig. 3 a plan view of the sears and trigger mechanism.

Similar letters denote like parts in the several figures.

In the present instance I have shown my improvement in connection with a hammerless gun; but it is equally applicable to guns 35 using exposed hammers, and, furthermore, I have not deemed it necessary to show the mechanism for cocking the hammers, as this is ordinary and well known.

A represents the breech of a gun, inclosing 40 the hammers B, which operate in the usual manner, and C C' are the sears, of ordinary construction, which serve to retain the hammers in their cocked position.

The above-named elements form no part of 45 my invention, since the latter has to do solely with the trigger mechanism.

D is the trigger, pivoted at its upper end 50 between ears E, formed with the breech, and provided with a rearwardly-extending projection F. This extension is slotted, so as to receive and form a bearing for the star-wheel

G, which latter is composed of eight points a b, the four points a being in one vertical plane, while the remaining four points b are in another vertical plane, the points in one 55 plane alternating with those in the other, for the purpose presently explained.

H is a spring-pawl secured to the breech and adapted to engage the points of the star-wheel in such manner as to rotate the latter 60 one step for every up-and-down movement thereof caused by the actuation of the trigger.

I is a spring-actuated retaining-pawl pivoted within the slot formed in the extension, and adapted to so engage the points of the 65 star-wheel as to prevent any retrograde movement of the latter.

Now, as the tails d e of the sears C C' extend just within the circle described by the points of the star-wheel, it will be seen that 70 on the upward movement of said wheel the sear whose tail is in the vertical plane of the inner horizontal point will be disengaged from the hammer, thereby permitting the latter to be sprung. As the star-wheel is elevated by 75 the pulling of the trigger, the pawl H engages a new point, so that when the trigger is released and the wheel descends said wheel will be caused to rotate one step, thus bringing to a horizontal position the next succeeding point, 80 which, being in a different vertical plane from its predecessor, will upon a second operation of the trigger actuate the reverse sear, and so on, first one and then the other hammer being sprung.

For example, if the trigger be operated 85 while the inner point of the a series is in a horizontal position, as shown, said point will engage and elevate the tail d of the sear C, which is in the same vertical plane therewith.

Now as the wheel falls upon the release 90 of the trigger, the pawl H, having engaged a point in the b series, will bring said point to a horizontal position, and upon the next operation of the trigger this latter point will engage and elevate the tail e of the sear C'. 95 Thus the hammers will be sprung alternately by the simple operation of the single trigger.

When my improvement is used in connection with hammerless guns, it is desirable to 100 be able to readily ascertain which of the hammers has been sprung. I accomplish this as follows:

Within recesses formed in the upper wall of the breech (only one being shown) are secured springs *h*, terminating in pins *i*, which project through openings, as shown. *l* is a notch cut in the upper portion of each hammer, the walls of which notch are adapted to cam against the lower ends of the pins and elevate the latter against the resiliency of their springs when the hammers are cocked. 15 When a hammer is sprung, its spring recedes within the notch, so that at a glance it may be ascertained which of the hammers has been sprung.

I claim—

15 1. In a double-barreled gun, the trigger carrying the star-wheel, as described, in combination with a stationary pawl secured to the lock-easing within the field of movement of said wheel, whereby, when the trigger is operated, 20 said wheel will be carried against said pawl,

thereby rotating the wheel, the sears against which said wheel operates when elevated, and a detent-pawl carried by the trigger and engaging with said wheel, whereby the latter is prevented from revolving backward, substantially as shown, and for the purposes set forth. 25

2. The combination of a trigger, carrying a star-wheel whose alternate points are in different vertical planes and are operated to rotate step by step by the springing of said trigger, 30 with the sears of a double-barreled gun, said sears having tails within the operative field of said wheel, substantially as and for the purpose set forth.

In testimony whereof I affix my signature 35 in the presence of two witnesses.

EBERHARD L. PUPKE.
